UNITED STATES PATENT OFFICE.

WILLIAM F. SMITH, OF BROOKLYN, NEW YORK, ASSIGNOR TO WESTERN ELECTRIC COMPANY, INCORPORATED, OF NEW YORK, N. Y., A CORPORATION OF NEW YORK.

TWISTING-MACHINE.

1,263,478.

Specification of Letters Patent. Patented Apr. 23, 1918.

Application filed January 17, 1916. Serial No. 72,493.

To all whom it may concern:

Be it known that I, WILLIAM F. SMITH, a citizen of the United States, residing at Brooklyn, in the county of Kings and State 5 of New York, have invented certain new and useful Improvements in Twisting-Machines, of which the following is a full, clear, concise, and exact description.

This invention relates to twisting machines, and more particularly to machines for forming a plurality of tinsel threads into a stranded conductor for use in telephone or switchboard cords.

Reference is hereby made to my copending application, Serial No. 148,273, filed Feb. 12, 1917, which is a division of this application and which claims subject-matter disclosed herein but not claimed herein.

One object of this invention is to produce a machine for stranding a plurality of tinsel threads into a symmetrical flexible conductor in such a manner that any strain or stress applied to the conductor is uniformly and equally distributed over the several threads, whereby the conductor life is greatly improved.

A further object of this invention is to provide means for automatically stopping the rotation of the twisting head immediately in case a tinsel thread breaks or slackens. This may comprise a mechanical tripping device for disengaging a friction clutch within one revolution of the twisting head.

This invention will be fully understood 35 from the following description considered in connection with the accompanying drawings, in which—

Figure 1 is a side elevation of a twisting machine embodying this invention;

Fig. 2 is a plan view of the twisting head with parts broken away to show the tension-equalizing and adjusting means;

Fig. 3 is a sectional view of the machine showing the driving members;

Fig. 4 is a sectional view on line 4—4 of Fig. 3;

Fig. 5 is a view of the main driving shaft and associate parts; and

Fig. 6 is a sectional view of a portion of 50 the twisting head.

Referring to Fig. 1 of the drawings, 10, 11 and 12 are vertical frame members of the twisting machine. Members 11 and 12 are connected near the top of the machine by a

horizontal member 13, and members 10 and 55 11 are connected near the base of the machine by 14, which is a horizontal extension of member 10.

The twisting head 15 shown in Fig. 2 is mounted on the supporting member 14 and 60 rotates in ball-bearings 16 of any well-known construction, as shown in Fig. 3. On the twisting head 15 and close to the periphery thereof is mounted a number of spool supports or spindles 20 for carrying 65 spools or bobbins 21. The spindles 20 are journaled in ball-bearings 22 and 23 of any well-known construction. On the sides of the spindles are spring members 24, which press against the inner peripheries of spools 70 21 for holding them in place and against rotation relative to the spindle upon which they are mounted.

At the center of the twisting head is an auxiliary frame 25 with outwardly extending arms 26, near the ends of which are secured, by means of screws 27, wheels 28 having two grooves in each of the peripheries thereof. Just below and in alignment with each wheel 28 is a grooved wheel 29 secured 80 to a vertical plunger 30 by means of screw 31. The vertical plunger 30 passes through an opening in the frame 15 and auxiliary frame 25, and is normally so held that the lower end of the plunger is flush with the 85 frame 15 at the opening therethrough. To each of the spindles 20 between ball-bearings 22 and 23 is secured a sleeve 32 having an annular groove 33 therein. A circular belt 34 passes around the spindles and in 90 grooves 33 for applying the necessary tension to the tinsel threads. To each end of the belt 34 is rigidly secured a metal tip or socket 35, which is pivotally secured, by means of screw 36, to equalizing links 37 95 pivotally supported on block 38, which is adapted to slide on threaded rod 39.

It will be seen that with the ends of the belt held in a definite fixed position, the rotation of the spindles would raise the flexible 100 belt to impart very non-uniform tension, that is, the rotation of the several spindles would cause the belt to impart the greatest tension to the spindles immediately on one side of the fixed position of the belt, and the 105 least tension to the spindles immediately on the opposite side of the fixed position, depending upon the direction of rotation

of the spindles. By means of equalizing links 37, the slack in the belt on one side of the links is given over to the opposite side, thereby maintaining a uniform tension on all of the spools. By turning the rod 39, the threaded portion thereon engages block 40 and imparts a longitudinal movement thereto which forces compression spring 41 against block 38, which in turn, 10 through the equalizing links 37, draws the belt 34 tighter around the spindles. It will, therefore, be seen that by the turning of a single member 39, the tension on the belt may be easily and readily adjusted.

15 Fig. 3 shows in section the transmission system for rotating the twisting head 15. The main driving shaft 42 carries a sprocket wheel 43, a friction clutch, Fig. 4, and a bevel gear 45. The bevel gear 45 meshes 20 with bevel gear 46, which is keyed to shaft 47. To shaft 47 is also keyed gear 48 which meshes with pinion 49, which in turn meshes with gear 50, which is secured to the twisting head 15.

25 The friction clutch shown in Figs. 3 and 4 consists of two semi-circular expandable members 51 and 52, which are held out of engagement with the inner periphery of cylinder 53, when the machine is not in operation, by means of contractile springs 54 and 55. The ends of expandable members 51 and 52 have beveled surfaces adapted to receive wedge-shaped blocks 56 and 57. Links 58 and 59 at one end engage the wedge-shaped 35 blocks 56 and 57, and at the other end engage extensions 60 and 61 of annular member 62, which is slidably mounted on shaft 42 and keyed thereto to rotate therewith. By sliding the annular member 62 along 40 shaft 42 so that the V-shaped blocks 56 and 57 are forced outwardly, the expandable members 51 and 52 are forced into engagement with the inner periphery of the cylinder 53.

45 Annular member 62 has an annular groove therein, into which is inserted a ring 63. To ring 63 is pivotally attached by means of screws 64 and 65, a clutch arm 66 which is bifurcated at one end to receive the ring 63. 50 The other end of the clutch arm 66 is pivotally secured to a link 67, which is in turn pivotally secured to an arm 68. The opposite end of arm 68 is connected by means of a contractile spring 69 to the clutch arm 66 at 55 a point intermediate of its connection with link 67 and its fulcrum 70, at which it is pivotally mounted on the frame of the machine. Arm 68 is rigidly secured to post 71. Arm 72 is also rigidly secured to post 71. 60 Tripping bar 73 is pivotally mounted on the frame 14 by means of screw 74 and engages arm 72 at 75. The tripping bar is normally held in engagement with arm 72 by means of contractile spring 76, which engages arm 65 77 and tripping bar 73. It will be seen that

the several parts of the automatic mechanical tripping device are shown in the drawings in their normal or non-tripped positions.

On the front of the machine is a bracket 78 for supporting a spool 79 carrying a tinsel thread or filler 80 for forming the center of the stranded conductor. Spring 81 and brake member 82 are carried by the bracket 78 for applying tension to the filler 80 as it is drawn from the spool 79.

75 The operation of the machine is as follows:

The tinsel thread or filler 80 is drawn from spool 79 around grooved pulley 83, up through the hollow spindle 18, thence 80 through a tube 84 which passes through the center of the auxiliary frame 25, and thence to the periphery of grooved wheel 85, at which point several threads of tinsel 86 are applied around the filler. The tinsel threads 85 86 are drawn from spools 21 over and along one groove of wheels 28, thence down and around grooved wheels 29, thence up and along the other groove of wheels 28, thence up to the periphery of the grooved wheel 85, where they are formed around the filler 80. From this point the stranded conductor passes over and around grooved wheel 87, thence back along another groove in wheel 85, and thence on to a suitable take-up device. Grooved wheels 85 and 87 are mounted on the cross member 13 and are preferable to a bushing for forming tinsel threads into a stranded conductor, there being less cutting effect between the tinsel and rotatable 90 wheels than between the tinsel and a bushing. The tinsel threads 86, in passing around grooved wheels 29, normally hold each of the plungers 30 against their own weight, the weight of wheels 29 and the action of compression springs 88, so that the ends thereof are flush with the openings in the twisting head 15, through which they 95 pass.

105 Should any one of the tinsel threads, carried by the twisting head, break or slacken, the plunger 30 supported thereby falls to the position shown in Fig. 6, and the end of the plunger, extending below its respective opening in the twisting head, is brought 110 into engagement with the tripping bar 73 within one revolution of the twisting head. The engagement of the plunger 30 and the tripping bar 73 causes a disengagement of the tripping bar 73 and arm 72 at the point 115 75. At the instant the tripping bar 73 and arm 72 disengage, tension spring 69 acting through arm 68, link 67 and clutch-arm 66, causes the friction clutch to release by 120 withdrawing the expandable members 51 and 52 from engagement with the inner periphery of the cylinder 53, thereby stopping the rotation of the twisting head.

125 The friction clutch may also be released manually by throwing handle 92, which 130

handle is loosely mounted on shaft 71, in the direction X, thereby bringing contact 89 into engagement with arm 77 at 90 and forcing tripping bar 73 out of engagement 5 with arm 72 through the medium of arm 77 and connecting link 91.

After a broken thread has been repaired or an empty bobbin replaced by a full one, and the wheel 29 and plunger 30 raised to 10 their normal positions by passing the tinsel thread 86 around wheel 29, the tripping bar 73 may be returned to its normal position, and the friction clutch placed in operative 15 position by turning the handle 92 in the direction Y, thereby bringing arm 72 and tripping bar 73 into engagement at 75.

What is claimed is:

1. In a machine for twisting strands, a tripping device, a revoluble head, a plurality of grooved wheels carried by said revoluble head and traversed by the strands, means for regulating the tension of said strands, a plurality of plungers independent of said tensioning means normally supported by the strands, and spring members for causing each plunger to engage said tripping device for stopping the rotation of the head upon breakage or slackening of the strand supporting said plunger.
2. In a twisting machine, a revoluble head, a plurality of strands carried thereby, means for regulating the tension of said strands, a plurality of grooved wheels carried by the head and traversed by said strands, a plurality of members carried by the head and normally supported by the strands, said members being independent of said tensioning means, and a plunger carried by each of said members and adapted

to separately engage said tripping device 40 for stopping the rotation of the head upon breakage or slackening of a strand.

3. In a twisting machine, a revoluble head, driving mechanism operatively connected therewith, a plurality of strands 45 carried by the head, means for regulating the tension of said strands, a plurality of grooved wheels carried by said revoluble head and traversed by said strands, a tripping device adapted when actuated to disconnect the driving mechanism, a plurality 50 of members carried by the head and normally supported by the strands, said members being independent of said tensioning means, and a plunger carried by each of 55 said members and adapted to engage said tripping device upon the slackening or breaking of a strand.

4. In a twisting machine, a revoluble head, driving mechanism operatively connected therewith, a plurality of spools of strands carried by the head, means for regulating the tension of said strands, a tripping device adapted when actuated to disconnect the driving mechanism, a plurality 60 of grooved wheels carried by the head and normally supported by the strands, and a plunger independent of said tensioning means carried by each of said wheels and adapted to be held out of engagement with 65 the tripping device by the strands, the slackening or breaking of a strand causing the plunger supported thereby to engage and actuate the tripping device.

In witness whereof, I hereunto subscribe 75 my name this 15th day of January, A. D. 1916.

WILLIAM F. SMITH.
